VEHICLE LICENSE PLATE FRAME

Stanley W. Yoder, Little Rock, Ark.

Application February 10, 1958, Serial No. 49,568

Term of patent 14 years

(Cl. D14—6)

Fig. 1

Fig. 2

Fig. 3

Fig. 4

Fig. 5

Figure 1 is a front perspective view of a vehicle license plate frame showing my new design;

Figure 2 is a rear elevational view thereof;

Figure 3 is an end view;

Figure 4 is a fragmentary rear view of a corner of the vehicle license plate frame; and

Figure 5 is a cross-sectional view taken on the line 5—5 of Figure 2.

I claim:

The ornamental design for a vehicle license plate frame, substantially as shown.
